(57) **CLAIM**

The ornamental design of a nozzle, as shown and described.

DESCRIPTION

FIG. 1 is a top perspective view of an embodiment of a nozzle showing a new design. The nozzle is attached to a spray gun, shown in broken lines, presenting a typical environment of the design.

FIG. 2 is a right side elevation view of the nozzle of the present design.

FIG. 3 is a left side elevation view, opposite of the view of FIG. 2, of the nozzle of the present design.

FIG. 4 is a top plan view of the nozzle of the present design.

FIG. 5 is a bottom plan view of the nozzle of the present design.

FIG. 6 is a front side elevation view of the nozzle of the present design.

FIG. 7 is a rear side elevation view of the nozzle of the present design.

FIG. 8 is an enlarged front side elevation view of the nozzle of the present design, with portions of the spray gun being not shown and with other portions shown in broken lines; and, FIG. 9 is an enlarged front side elevation view of a further example of a nozzle of the present design, with portions of the spray gun being not shown and with other portions shown in broken lines.

Broken lines in the present drawings are presented to show an example of the environment of the new design. The portions shown in broken lines form no part of the claimed design.

1 Claim, 7 Drawing Sheets
